UNITED STATES PATENT OFFICE.

JULIO NAVARRO BRIONES, OF CUENCA, SPAIN.

COMPOUND FABRIC.

1,306,518.

Specification of Letters Patent. Patented June 10, 1919.

Application filed August 8, 1917. Serial No. 185,147.

To all whom it may concern:

Be it known that I, JULIO NAVARRO BRIONES, a subject of the King of Spain, and resident of Cuenca, in the Province of Cuenca, Spain, have invented certain new and useful Improvements in Compound Fabrics, of which the following is a specification.

The invention relates to compound fabrics in which cork, associated with a textile material, is used as garments to prevent the loss of heat from the human body. As cork is also a bad conductor of electricity, the same construction provides safely against electric shocks.

According to the invention, a layer of cork dust, or of thin slices of cork, is inclosed between two sheets of textile fabric, which are sewn together in directions crossing each other, so as to leave small spaces within which the insulating material is contained and held in position. The sides of the inclosed spaces are, preferably, about a centimeter in length and the thickness of the cork layer, preferably, from one to two millimeters.

Two or more superimposed thicknesses of the compound fabric may be employed where special protection is required, and in this case it is advisable that the seams of one thickness should coincide with the centers of the spaces of the adjacent thickness.

In the accompanying drawings Figure 1 shows an example of a portion of a garment composed of two sheets of fabric within which is contained the finely divided cork. Fig. 2 is a section of the compound fabric. Fig. 3 shows two superimposed layers of the compound fabric.

Referring to Figs. 1 and 2, A and B are the two sheets of fabric between which the cork particles C are inclosed and are kept in position by seams D which cross the fabric at right angles. Two such compound fabrics F and G are shown superimposed in Fig. 3; in this case the seams would be arranged so that the stitches of one layer cross the centers of the spaces inclosed by the stitches of the other layer.

If cork in small shavings or the like is employed as the insulating medium, the compound fabric may be caused to pass over a cylinder, or between cylinders, provided with suitably disposed small teeth or pins which perforate the material and thereby ventilate it. After leaving the cylinders the fabric is as smooth and soft as chamois leather.

Garments of the type described are light, flexible, hygienic, since they allow of the ready escape of perspiration, and they protect their wearers against shock from electrified wires; the materials used are inexpensive and if the outer fabrics are damaged others can be applied to the same insulating material.

Having thus described the nature of the said invention and the best means I know of carrying the same into practical effect, I claim:

1. A garment comprising two sheets of textile fabric stitched together in directions crossing each other, so as to leave small rectangular spaces containing cork fragments.

2. A garment comprising two sheets of textile fabric stitched together in directions crossing each other, so as to leave small spaces containing thin shavings of cork.

3. A perforated garment comprising two sheets of textile fabric stitched together in directions crossing each other, so as to leave small spaces containing cork fragments, substantially as described.

4. A garment comprising two superimposed compound fabrics, each compound fabric consisting of two sheets of textile fabric stitched together in directions crossing each other, so as to leave small spaces containing cork fragments, the stitches of one fabric crossing the center of the spaces of the other fabric.

In testimony whereof I have signed my name to this specification in presence of two subscribing witnesses.

JULIO NAVARRO BRIONES.
